(57) **CLAIM**

The ornamental design for an accessory for blender, as shown and described.

DESCRIPTION

1. Accessory for blender

1.1 is a perspective view of an accessory for blender showing my new design.

1.2 is a front elevational view thereof;

1.3 is a rear elevational view thereof;

1.4 is a right side elevational view thereof;

1.5 is a left side elevational view thereof;

1.6 is a top plan view thereof; and

1.7 is a bottom plan view thereof.

The portions of the accessory for blender shown in broken lines form no part of the claimed design.

1 Claim, 6 Drawing Sheets
